UNITED STATES PATENT OFFICE.

PETER F. AUGENBRAUN, OF STAMFORD, CONNECTICUT, ASSIGNOR TO THE YALE & TOWNE MANUFACTURING COMPANY, OF STAMFORD, CONNECTICUT.

RIM-LATCH.

No. 918,492.

Specification of Letters Patent.

Patented April 20, 1909.

Application filed May 22, 1908. Serial No. 434,404.

To all whom it may concern:

Be it known that I, PETER F. AUGENBRAUN, of Stamford, in the county of Fairfield and State of Connecticut, have invented certain new and useful Improvements in Rim-Latches; and I do hereby declare the following to be a full, clear, and exact description of the invention, such as will enable others skilled in the art to which it appertains to make and use the same.

My invention relates to an improvement in rim latches, the object being to provide a lock having a bolt which when projected to a position past its normal locking position, will be automatically deadlocked against retraction by an instrument inserted between the face plate of the lock and strike plate.

A further object is to provide means whereby the latch bolt may be reversed so as to permit the latch to be used on doors swinging either inwardly or outwardly.

With these objects in view my invention consists in the parts and combinations of parts as will be more fully described and pointed out in the claims.

In the accompanying drawings, Figure 1 is a view in elevation showing the bolt in one position. Fig. 2 is a similar view showing the bolt in its second or double thrown position. Figs. 3 and 4 are similar views of the rear of the lock the face plate being removed. Fig. 5 is a view in rear elevation showing the bolt retracted. Fig. 6 is a detached view of the bolt and its carrying frame; the parts being in their normal position when the bolt is projected either on a single or double throw. Fig. 7 is a similar view of these parts showing their relative positions when the bolt is retracted. Fig. 8 is a detached view of the bolt partly in section showing the manner of reversing the bolt head and Fig. 9 is a detached view of the bolt carrying frame.

1 represents the bolt head provided at its rear end with a socket for the reception of the cylindrical end 2 of the bolt shank 3, the said end 2 being secured in the socket by a pin 4 passing through a hole in the head, and resting in a peripheral groove in the cylindrical end 2, thus preventing a separation of the head and stem, but permitting the head to be turned so as to adapt itself to doors opening either inwardly or outwardly.

The shank 3 is preferably shaped as shown in the drawings, that portion thereof im-

mediately in rear of the head 1 of the bolt, being in the plane of the longitudinal center of the latter, while the rear free end of the shank, is in a plane in front of the center, and adjacent to the front or outer wall of the lock case. Formed integral with the shank at the juncture of the two sections of the latter, is the shoulder 5, having a hole 6, through which the guide rod 7, secured to the carrying frame 8 passes.

The carrying frame 8 consists of a body 8^a and two ends 8^b, the guide rod 7 being secured at its ends to the ends 8^b of the frame. The rear or inner portion of the body 8^a of the carrying frame, is provided with a shoulder 9, adapted to be engaged by the end of arm 10 on the hub 11 of the knob spindle 12, for retracting, or moving the carrying frame 8 rearwardly, and for moving the bolt back to its single throw position, and mounted on the body of the carrying frame, with its rear free end adjacent to said shoulder 9, is the spring pressed tumbler 13. The hub 11 of the knob spindle 12 is provided with a projecting lug adapted to be engaged by projections from a hub (not shown) actuated by ordinary key mechanism. The tumbler 13 rests in a position to bear against the end of arm 10 on the hub, and operates to yieldingly hold said arm against the shoulder 9 when the bolt is in its single throw position, and against the rear end of lug 14 on the shank of the bolt, when the latter is in its double thrown and deadlocked position. The lug 14 on the rear end of the shank of the bolt is engaged by the arm 15 on the hub, for retracting the bolt from its single throw position. Mounted on the guide rod 7 is the spring 16, which tends to yieldingly hold the bolt in its projected positions. When the bolt is double thrown, it is deadlocked against manipulation by a thin instrument introduced between the face plate of the lock and the keeper, by the end of the arm 10 bearing against the rear face lug 14 on the end of the bolt shank, the arm 10 being limited in its movement by the engagement of the arm 15 on the hub of the knob spindle, with the post 15^a fixed to the lock case.

In the operation of the lock, if the bolt be double thrown and deadlocked, a rotation of the hub 11 in the proper direction carries the end of arm 10, away from the rear end of the bolt shank and into contact with the shoulder 9. During its movement, it pushes

the tumbler 13, which yielding operates simply to hold the arm 10 against free or accidental movement, out of its path, and when it engages the shoulder 9 it moves the carrying frame 8 and its connected bolt back to its single throw position. By now continuing the turning movement of the knob 12^a in the same direction, the arm 15 on the hub engages the front face of the lug 14 on the rear end of the shank of the bolt, and forces the bolt to its fully retracted position, in which position it may be retained by the slide 17 operated by thumb piece 18 engaging lug 19 on the bolt shank. By disconnecting the slide 17 from the bolt, the latter will be forced by the spring 16 out to its single throw position, and by rotating the knob 12^a in the opposite direction, the arm 10 will engage the tumbler and lift same out of its path. Ordinarily the friction between the end of arm 10 and the tumbler 13 will be sufficient to move the carrying frame 8 and its connected bolt forwardly to the double thrown position of the latter, but if the arm 10 slips on the tumbler, it will engage the shoulder 14 on the end of the bolt shank, and positively force the bolt and its connected carrying frame forwardly to the double thrown position of the bolt.

From the foregoing it will be seen that the bolt may be partly projected from the lock case, into what I have termed its normal locking position, or be projected still farther to what I have termed the double throw position, and when double thrown, will be deadlocked against any thin instrument applied against the bolt head between the face plate of the lock and the strike plate. When the bolt is in its normal locking position the carrying frame rests adjacent to the rear end of the lock case, and when double thrown, the frame is moved forwardly toward the front face of the lock. The independent movements of the bolt are guided by the bolt head in its slot in the face plate and the guide rod 7, and the movements of the carrying frame are guided by the lugs 20 cast integral with the lock casing.

The hub of the lock is connected in the usual manner with the key lock on the outside of the door.

It is evident that many slight changes might be resorted to in the relative arrangement of parts shown and described without departing from the spirit and scope of my invention hence I would have it understood that I do not wish to confine myself to the exact construction and arrangement of parts shown and described, but

Having fully described my invention what I claim as new and desire to secure by Letters-Patent, is:—

1. In a lock, the combination with a carrying frame and a bolt, the shank of which has a movable connection with said frame,

of bolt actuating mechanism provided with means for moving said frame and bolt inwardly, and also with means for moving the bolt inwardly independently of the frame.

2. In a lock, the combination with a bolt, and means for retracting the same, of means actuated by the retracting means for projecting the bolt beyond its normal locking position, and for restoring it to such normal position and means for deadlocking the bolt when the latter is projected beyond its normal position.

3. In a lock, the combination with a bolt, of a hub for moving the bolt to a projected position beyond its normal locking position, for deadlocking the bolt when so projected and for retracting the bolt.

4. The combination with a bolt and a connected frame, of bolt retracting means adapted to first engage the frame and move same rearwardly for partly retracting the bolt, and then engage the bolt proper for completing the retracting movement.

5. The combination with a movable frame and a bolt connected thereto, the said bolt being movable with the frame and movable on the frame, of means for moving the frame and bolt outwardly, and for moving the frame and bolt inwardly, and also for moving the bolt inwardly on the frame independently of the frame.

6. In a lock, the combination with a sliding frame and a bolt having a movable connection therewith, of a spindle carrying means for moving the frame and bolt outwardly, for moving the frame and bolt inwardly and for moving the bolt inwardly independently of the frame.

7. In a lock, the combination with a bolt comprising a shank and a head the latter being reversible on the shank, and a sliding frame having a sliding connection with the bolt shank, of a spring for normally holding the bolt in its locking positions and means for moving said bolt and frame outwardly and inwardly, and for moving the bolt inwardly from its normal locking position.

8. In a lock, the combination with a sliding frame and a bolt connected thereto so as to be moved therewith positively in one direction and yieldingly in the other direction, of means for moving the frame and bolt outwardly and inwardly, and for moving the bolt inwardly from its normal locking position.

9. In a lock, the combination with a sliding frame having a guide rod, a bolt, the shank of which has a connection with said guide rod, and a spring tending to normally hold the bolt projected, of actuating mechanism for moving the sliding frame outwardly and inwardly and also having means for moving the bolt inwardly from its normal locking position.

10. In a lock, the combination with a sliding frame having a guide rod, a bolt the shank of which has a connection with said rod and a spring tending to normally hold the bolt projected in both positions of the sliding frame, of actuating mechanism for moving the frame and bolt outwardly and inwardly and for deadlocking the bolt when moved outwardly with the frame, and also

provided with means for moving the bolt 10 inwardly from its normal locking position.

In testimony whereof, I have signed this specification in the presence of two subscribing witnesses.

PETER F. AUGENBRAUN.
